(57) **CLAIM**

The ornamental design for a posterior stabilized insert, as shown and described.

DESCRIPTION

FIG. 1 is a perspective view showing the front, top and left sides of the posterior stabilized insert;

FIG. 2 is a front elevation view of the posterior stabilized insert;

FIG. 3 is a rear elevation view of the posterior stabilized insert;

FIG. 4 is a right side elevation view of the posterior stabilized insert;

FIG. 5 is a left side elevation view of the posterior stabilized insert;

FIG. 6 is a top plan view of the posterior stabilized insert; and,

FIG. 7 is a bottom plan view of the posterior stabilized insert.

The broken lines shown in the drawings represent portions of the posterior stabilized insert that form no part of the claimed design.
